UNITED STATES PATENT OFFICE.

FRED HUTCHENS, OF VALTON, WISCONSIN.

OIL-STOVE ATTACHMENT.

1,064,485.

Specification of Letters Patent. Patented June 10, 1913.

Application filed November 10, 1910. Serial No. 591,667.

To all whom it may concern:

Be it known that I, FRED HUTCHENS, a citizen of the United States, residing at Valton, in the county of Sauk, State of Wisconsin, have invented certain new and useful Improvements in Oil-Stove Attachments; and I do hereby declare the following to be a full, clear, and exact description of the invention, such as will enable others skilled in the art to which it appertains to make and use the same.

This invention relates to improvements in stoves and the object of the same is to provide a warming oven for kerosene oil stoves having communication by a heat conducting pipe with one of the burners of the stove.

Another object of the invention is to provide a stove of this type with a removable grate adapted for use in connection with cereals and other foods requiring a slow fire and comprising upper and lower metallic grate sections and an intermediate section of asbestos or like heat insulating material.

With the above and other objects in view the invention consists in certain constructions, combinations and arrangements of parts, clearly described in the following specification and clearly illustrated in the accompanying drawings, in which:

Figure 1 is a perspective view of a stove provided with the improved warming oven with a portion of the stove broken away to show the heat conducting pipe. Fig. 2

is a detail plan view of the improved grate. Fig. 3 is a cross sectional view thereof. Fig. 4 is a plan view of an upper metallic grate section. Fig. 5 is a similar view of an intermediate asbestos section. Fig. 6 is a similar view of a lower metallic grate section.

Referring to the accompanying drawings illustrating the preferred embodiment of the invention 5 denotes a stove having openings in the top thereof which are covered by grates 6. Beneath the openings covered by the grates 6 oil burners are arranged, two of said burners being shown as indicated by the numeral 7. The heat conducting pipe 8 communicates at one end with a warming oven 9 mounted on the stove 5 and has its other end disposed over a portion of the burner 7 and extended in a horizontal position therefrom so that a portion of the heat

generated by said burner when the same is 55 in operation will be conducted to the warming oven 9. By means of this arrangement an ordinary oil stove may be provided with an oven for keeping food or dishes warm.

In Figs. 2 to 6 inclusive, I have illustrated 60 a construction of the improved grate, which comprises an upper metallic grate section 10, a lower metallic grate section 11 and an intermediate asbestos section 12 which is secured to the upper and lower metallic 65 grate sections 10 and 11 by means of rivets or screws 13. The intermediate asbestos section 12 which may be of any other suitable heat insulating material, is provided with openings 14 through which the heat 70 may pass and said section is arranged for rotation between the upper and lower metallic grate sections and in such a way that the openings may be partly closed or wholly closed by rotating said section. In the latter construction, slots 15 are provided for engagement by the fastening rivets or screws 13 so as to hold the asbestos section 75 and permit sliding movement thereof.

By means of the improved grate the heat 80 of any one of the burners of a stove may be considerably reduced so as to provide a slow fire for cooking cereals and like foods which are spoiled by rapid cooking.

The improved warming oven can be used 85 with gasoline stoves as well as kerosene stoves.

What is claimed is:

The combination with an oil stove comprising a casing having openings in its top 90 portion and burners vertically mounted within the casing; of grates mounted in openings in the top of the casing over the burners and spaced from the latter, each of said grates comprising circular upper and 95 lower plates of metal having radial openings therethrough and an intermediate section of asbestos slidably engaged between said plates and provided with openings adapted to be moved into and out of registry 100 with the openings in the plates.

In testimony whereof, I affix my signature, in presence of two witnesses.

FRED HUTCHENS.

Witnesses:

WILLIS SURSEY,
M. SENGLIK.
